Inventor:

William H. Voss,
by Wallace R. Lane.

Atty.

UNITED STATES PATENT OFFICE.

WILLIAM H. VOSS, OF DAVENPORT, IOWA.

SAFETY WRINGER CLOTHES FEEDER.

Application filed April 2, 1923. Serial No. 629,306.

My present invention relates broadly to a means for handling wet clothing, particularly when hot, and more specifically to means for taking clothing out of hot water 5 and feeding the same to a wringer, thus avoiding the necessity of handling the same with the hands.

Among the objects of my invention are to provide a construction of the character 10 stated by means of which clothing can be readily picked up without getting the fingers burned; to provide means of the character indicated which can be used to feed clothing to a wringer without danger of 15 getting the hands caught; to provide means of the character indicated which will permit clothing to be fed to a wringer without danger of said means being drawn in between the wringer rolls; to provide means of the 20 character indicated which will insure clothing being fed in between the rolls of a wringer and which will nevertheless be incapable of itself passing in between the wringer rolls; to provide means for feeding 25 fabrics to the rolls from any desired angle; to provide means adapted to suctionally hold the fabrics onto the feeder; and such further objects, advantages, and capabilities as will later more fully appear.

My invention further resides in the combination, construction and arrangement of parts illustrated in the accompanying drawings, and, while I have shown therein certain embodiments of my invention, I desire 35 the same to be understood as illustrative only and not as limiting said invention.

In the drawings annexed hereto and forming a part hereof Fig. 1 is a perspective view of one form of my invention, showing the 40 same in connection with a wringer; Fig. 2 is a plan view of the construction shown in Fig. 1. Fig. 3 is an elevation of this construction. Fig. 4 is a longitudinal section of the same construction, the handle in this 45 figure and also in Figs. 2 and 3 being broken away, to reduce the length thereof. Fig. 5 is a plan view of another form of execution of my invention, while Figs. 6 and 7 are respectively end and edge views and 50 Fig. 8 a longitudinal section of this construction. Fig. 9 is a plan view of still another form of execution of this invention, while Figs. 10 and 11 are, respectively, side elevation and longitudinal section of this 55 construction. Figs. 12 and 13 are respec-

tively a plan view and a longitudinal section of still another form of execution of this invention.

Referring more in detail to the drawings, numeral 1 designates the handle and 2 the head of this construction upon which the clothes are adapted to be supported. The substantially cylindrical head has as a part thereof, and upon one side, an extension or projection 3, in which is located a socket 60 for the reception of one end of the handle 1. The body 5 of the head, in the construction shown on sheet 1 preferably has an arcuate periphery, and the corresponding part shown in the constructions on Sheet 2, is 65 provided with a flange or lip 6, preferably also arcuate and somewhat tapered toward its forward edge. By means of this flange 70 any clothing which is picked up by the clothes feeder may be forced in between the 75 rolls of the wringer as shown in Fig. 1. It will be understood that the part of the body 5 below the flange 6 may, if desired, be made of the same thickness as that above the flange, but it is preferred to make the same 80 in the form shown in Figs. 3 and 13, since this permits the implement to be used with less interference with the cross bar which is present in many wringers, extending from 85 side to side thereof.

In the form of construction shown in Figs. 5 to 8, inclusive, the head 5 includes a pair of arms 7, connecting the extension 3 with the body 5, said arms being extended into flanges 8 perforated for the reception of 90 screws or the like 9 which extend through the perforations into the ends of a pair of rollers 10. It will be seen that in this construction, as in the preceding construction, the flange 6 extends forwardly sufficient to 95 enable clothing to be fed in between the rolls of the wringer, but, preferably, not far enough to allow itself to be drawn in between said rolls.

In the form of construction shown in Figs. 9, 10, and 11, the general outline of the head is much the same as in the form last above described, but the rollers 10 are omitted, and the head 5 is much larger, much the same ultimate result being secured in these 105 two constructions. The primary difference between these two constructions is, the one shown in Figs. 5 to 8 is lighter in weight than the other and the rollers will turn on their pintles 9 as clothing is drawn 110

between the wringer rolls, thus permitting a greater degree of ease in operation. It will be noted that the form of construction shown in Figs. 1 to 4, inclusive, has an advantage 5 over the other constructions in that due to the rolling, arcuate surface of the head 5 the clothes feeder may take a position at right angles to the wringer rolls or may take 10 a considerable angle therewith, when the clothing is being fed to the wringer, while with the other forms the feeding is not so accurate and positive when the handler makes a considerable angle with the wringer rolls.

15 It will be clear that the amount of metal required, as well as the weight thereof, may be considerably reduced in the form of execution shown in Figs. 1 to 4, or any form similar thereto, by making the entire head 20 hollow, it being necessary merely to use an amount of metal sufficient to furnish the necessary strength. An illustration of such a construction is shown in Figs. 12 and 13 in which the head 5 is provided with a hole 25 low or cavity 12 which communicates through an opening 13 with the opposite side of the head. By providing the head 5 with the cavity 12 and the perforation 13, a very beneficial action is secured. For instance, when the clothes or fabrics are lifted 30 out of the tub by means of the device the water will run down through the hole or perforation 13 in the bottom of the cup thereby creating a substantial sucking action upon 35 the clothes tending to draw them down tight into the cup, and thereby making it easier to lift the clothes up out of the tub and feed them into the wringer, as otherwise the clothes tend to slip off the end of the cup.

40 This opening may be either larger or smaller as desired. Various other forms of execution of the invention herein disclosed will suggest themselves to one skilled in the art and it is therefore understood that the specific 45 description of structure set forth above may be departed from without departing from the spirit of my invention.

Having now described my invention, I claim:

1. A laundry device operable as a clothes feeder for the wringer rolls of a washing machine, comprising a head provided with a handle, said head being formed with a cavity to assist in holding fabrics on said head and having a flange projecting forwardly 55 therefrom.

2. A device for feeding clothes between the rolls of wringers, comprising a head having a substantially cylindrical wall provided with a peripheral tapering flange, said head having a socket on a peripheral portion 60 into which the ends of the flange merge and a handle secured in the socket.

3. A device for feeding clothes between the rolls of wringers comprising a substantially cylindrical member having a peripheral portion thereof provided with a lateral projection suitably joined to a handle, the cylindrical peripheral wall of said member being provided with an outstanding relatively thin arcuate lip adapted to be disposed 65 between the rolls.

4. A device for feeding fabrics between the rolls of wringers comprising a member formed with upper and lower arcuate surfaces 75 adapted to contact with the upper and lower wringer rolls, said member having a relatively thin arcuate lip disposed intermediate said surfaces and projecting forwardly to be positioned between the rolls, so said arcuate surfaces being substantially parallel to said arcuate lip.

5. A device for feeding fabrics between the rolls of a wringer comprising a member having a head formed with an arcuate surface adapted to contact with a wringer roll, said head having a relatively thin arcuate lip projecting forwardly from said surface, said arcuate surface being parallel with 85 said lip.

In witness whereof, I hereunto subscribe my name to this specification.

WILLIAM H. VOSS.
